(57) CLAIM

The ornamental design for a sandal as shown and described.

DESCRIPTION

FIG. 1 is a first perspective view of a sandal showing my new design;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof; and,

FIG. 8 is a second perspective view thereof.

FIGS. 1–8 depict a left foot sandal of a pair of sandals; a right foot sandal of the pair of sandals, which is a mirror image of the preceding embodiment, is also claimed but not shown. The broken lines in the drawings represent portions of the left foot sandal that form no part of the claimed design.
